ABSTRACT

A dryer for articles such as clothes including brackets which are rigidly mounted on the inner or outer sides of an openable window of a dwelling. Associated with the brackets is an article hanging frame that can be swung between a vertical storage position parallel to a wall of the dwelling, either inside or outside of the window, and a horizontal operative position. In the operative position the frame can be slid horizontally between a location substantially within the dwelling and a location substantially outside the dwelling. When the frame is in operative position inside the dwelling wet articles to be aired easily can be loaded onto the same after which the frame is slid through the window to its external location where the articles can be dried or aired in fresh air and sun and with the aid of any wind that may be blowing, thereby facilitating and improving drying and airing, and preventing an increase of humidity and providing more available space within the dwelling. Thereafter the frame is slid back into the dwelling through the window for unloading the dried or aired articles. When the frame is in its vertical storage position it is inconspicuous and takes up very little living space.

INDOOR LOADABLE OUTDOOR CLOTHES DRYER

BACKGROUND OF THE INVENTION

1. Field of the Invention

A clothes dryer wherein the drying frame can be swung between an erect storage position against a wall of a dwelling and a horizontal operative position in which it can be slid back and forth through a window between the interior and exterior of the dwelling.

2. Description of the Prior Art

Equipment for the drying of clothes has experienced a long and varied history. Probably the first equipment employed was a clothes line that was strung at a person's height between vertical poles, at a time when the principal dwellings were single family homes. As multiple apartment dwellings came into vogue in urban areas, the occupants of these dwellings could not use clothes line poles in the limited yard space available so they resorted to clothes lines strung between building walls or between apartments and tall poles in a yard, the lines usually travelling about pulleys to facilitate loading and unloading of clothes at an apartment window. Both foregoing arrangements caused an unsightly clutter.

More compact, neater arrangements for drying clothes have become available. For example, in private homes an apparatus was used that consisted of a single pole, usually set up rather close to the house, that, like an umbrella, was provided with foldable radial arms near its top between which several runs of clothes line were strung. For apartments, clothes hangers were sold which constituted either a non-collapsible frame with clothes lines strung thereon or a foldable frame without a clothes line. The non-collapsible frame was suspended by pulleys and cords from a ceiling, frequently over a bathtub, and could be raised or lowered, being loaded when low and raised for drying. The foldable frame usually was placed in a bathroom and included a frame that could be raised or lowered and on which radial arms were mounted. The arms could be swung between vertical and horizontal positions in the latter of which they could be spread apart. The frame was lowered and the arms raised for storage and, for drying, the arms were swung to horizontal position and loaded and then the frame was raised so that people could walk under the wet clothes.

In another collapsible form of interior dryer a pair of pantographs connected by bars was used. This could be set up anywhere in a dwelling and, when collapsed, could be stored in any convenient place, e.g. a closet or basement. It opened vertically from a base to receive wet clothing for drying.

The pieces of foregoing equipment were purely mechanical and, except for the ground level lines and the umbrella-type pole were specifically designed for apartment dwellers.

More recently, drum type dryers have been made in which drying was performed by electrical or gas heaters. These found favor in private homes, in some of the better apartment houses and in laundries where individual members of the public do their own washing. However, they were not adapted to be used in many apartment houses, particularly in the older apartment houses where the electric and gas lines did not have the capacity to operate the dryers; nor was their use fa-

vored in many apartment houses, where they were placed in the basement or in other locations remote from a user's apartment and were shunned due to the fear of walking through corridors.

It also has been proposed in U.S. Pat. No. 581,931 to provide a clothes dryer in which a drying frame is translatable in a horizontal plane from under a porch or veranda roof to outside of the walls of a building. However, this latter patent can only be used in a private dwelling and, there, only in association with a windowless opening.

As will be apparent, with all the above indoor dryers, except for gas and electric dryers which were externally vented, there were certain undesirable side effects. For example, drying of clothes in a room substantially increased the humidity, this being unpleasant to the occupants, particularly in warm weather, and when the increase was sufficiently high inducing mildew. Moreover, drying in an enclosed space was a somewhat lengthy procedure, due to the increase in humidity and to the lack of movement of the ambient air. In addition, indoor drying of all kinds, as distinguished from outdoor drying, lost the beneficial effects of the sun among which are germicidal action and, for white clothes, bleaching. Ultra-violet lamps have been used in gas and electric dryers, but they are not as beneficial as the sun itself.

Another disadvantage of indoor clothes dryers is that they consumed a disproportionately large amount of living space for the function they served. Particularly when extended, if they were of the expandable type, they occupied a considerable percentage of living space that in modern dwellings, where space is expensive, is highly undesirable.

SUMMARY OF THE INVENTION

PURPOSES OF THE INVENTION

It is the principal object of the present invention to provide a clothes dryer which is specially designed for use in multiple apartment dwellings, although it also can be used to advantage in private houses, and which dryer overcomes all of the foregoing drawbacks.

It is another object of the invention to provide a dryer of the character described which constitutes relatively few and simple parts, is inexpensive to make, can be merchandised at a low price, is highly efficient in operation, can be manipulated without danger and without instructions by inexperienced and clumsy people, and lends itself to mass production.

It is another object of the invention to provide a dryer of the character described which can be loaded with articles such as clothes from inside a room and which can, despite its interior loading site, be manipulated to a site in which it is outside a dwelling so that the clothes will be exposed to the wind and the sun and will not tend to build-up vapor within the room.

It is another object of the invention to provide a dryer of the character described which can, with extreme ease and rapidity, be moved between an internal loading and unloading location and an external drying location.

It is another object of the invention to provide a dryer of the character described which can be mounted either inside or outside a room and the mounting of which can be accomplished within but a few minutes and by people not having any particular skills, and without the assistance of special tools.

It is another object of the invention to provide a dryer of the character described which is so designed that it is capable of having hung therefrom a large quantity of wash in a rather small space so that, although adapted to be mounted in standard window openings, none of which is particularly wide, it can with ease have hung therefrom a full load of wash from a conventional washing machine.

It is another object of the invention to provide a dryer of the character described which, despite the fact that it is designed to be mounted in a standard, not overly large, window opening of a multiple apartment dwelling, can have hung therefrom large items such as sheets and blankets

It is another object of the invention to provide a dryer of the character described which is capable of being mounted in any window opening regardless of the type of window therein as, for example, which is capable of being mounted in a window opening having windows, casement or double-hung sash type.

It is another object of the invention to provide a dryer of the character described which, when mounted, is solidly installed and, therefore, can be safely secured at any floor of an apartment house without fear of an untoward accident.

It is another object of the invention to provide a dryer of the character described which is easy to dismount from a window opening so that if its normal storage position is outside of a building wall it can be brought inside to a safe place and kept there while the dwellers are away, as, for example, on a vacation.

It is another object of the invention to provide a dryer of the character described which is well suited for use in any one of the four seasons, even during the winter when outdoor conditions are not suitable for drying and the dryer should function solely as an indoor dryer.

It is another object of the invention to provide a dryer of the character described which, when stored, lies flat against a wall of a building, being disposed either inside or outside the building.

It is another object of the invention to provide a dryer of the character described which, when installed inside a building, lies, when flat, so close to the interior surface of the building wall that it easily can be concealed by an overlying window ornament such as a drape.

It is another object of the invention to provide a dryer of the character described which, when mounted on the exterior surface of a wall of a building, lies so close to the wall in storage position that it does not constitute a fire hazard.

It is another object of the invention to provide a dryer of the character described which, when in storage position, is so inconspicuous that it does not detract from the appearance of a room, if inside, or of a dwelling, if outside.

All in all, it is an object of the invention to provide a clothes dryer of the character described which is characterized by its ability to be loaded and unloaded from inside a building and yet to have clothes thereon directly exposed to the outside ambient air at a location outside the building, and, moreover, which, when not in use, lies flat against a wall of the building.

Other objects of the invention in part will be obvious and in part will be pointed out hereinafter.

BRIEF DESCRIPTION OF THE INVENTION

The clothes dryer of the present invention includes two brackets, each designed to be rigidly attached to the sides of a window opening, the mounting either being on the inside or the outside of the window depending upon the type of sash employed. The mounting can be changed from outside a window for spring, summer or fall to inside a window for winter. With a double-hung window the brackets can be secured at the inside or the outside. However, with a casement window the brackets must be secured to the inside of the window opening. The brackets are transversely registered across the width of the window opening and, aside from the arrangement for fastening to the sides of the window opening, essentially constitute a pair of parallel vertical tracks. A different shoe is pivoted to a high point on each track, the pivoting being about coincidental horizontal axes. A drying frame slides in the shoes and, since the drying frame is a rectangle, the shoes are maintained in identical angular orientations. When the shoes are horizontal the drying frame will be horizontal and can be slid on the shoes from a location inside a dwelling to a location outside the dwelling, regardless of whether the brackets are inside or outside the window. When the shoes are swung to vertical positions the shoes and the drying frame lie against the wall of the dwelling at which the brackets are mounted. A suitable mechanism is included to facilitate swinging of the shoes and frame between horizontal and vertical positions. The swinging mechanism disclosed constitutes a different rider that slides vertically on each track. Each rider is connected to a portion of the associated shoe at a point remote from the pivotal axis by a link pivotally connected at one end to the shoe and at the other end to the rider. When the riders are low on the tracks they lower the distal ends of the shoes to a horizontal operative position, and when the riders are raised they elevate the distal ends of the shoes to a vertical storage position. Means is included to lock the riders in their low position and to lock the shoes in their raised position. Means also is included to prevent the frame from sliding off the shoes in an outward direction so that the frame cannot ride off the shoes and fall to the ground.

The invention accordingly consists in the features of construction, combinations of elements, arrangements of parts and series of steps which will be exemplified in the device hereinafter described and of which the scope of application will be indicated in the appended claims.

BRIEF DESCRIPTION OF THE DRAWINGS

In the accompanying drawings in which are shown various possible embodiments of the invention:

FIG. 1 is a fragmentary elevational view of the outside of a window opening with the dryer embodying the present invention secured to the sides thereof and disposed in vertical position;

FIG. 2 is a vertical sectional view through the window opening and dryer illustrated in FIG. 1;

FIG. 3 is a fragmentary view similar to FIG. 2 but showing the dryer in operative position and with the dryer frame inside the building ready to be loaded;

FIG. 4 is a view similar to FIG. 3 but illustrating the dryer frame disposed externally of the building and with clothes hung thereon;

FIG. 5 is a fragmentary end view of the dryer in the position shown in FIG. 4;

FIG. 6 is a view similar to FIG. 2 but showing the dryer mounted inside the building;

FIGS. 7, 8, 9 and 10 are enlarged cross-sectional views showing various details of the dryer, the same being taken substantially along the lines 7-7, 8-8, 9-9 and 10-10, respectively, of FIG. 4; and

FIG. 11 is another enlarged cross-sectional view showing a different detail of the dryer, the same being taken substantially along the line 11-11 of FIG. 2.

PREFERRED EMBODIMENTS OF THE INVENTION

Referring now in detail to the drawings and, more particularly, to FIGS. 1-5 and 7-11, the reference numeral 20 denotes a wall of a building having a window opening 22 therein. A window casing 24 is securely mounted in the window opening. The casing illustrated is for a double-hung window 26 including an upper sash 28 and a lower sash 30. The sashes slide in individual channels 32, 34, respectively, of the casing. Connecting the casing channels are a top header 36 and a sill 38, the latter sloping outwardly and downwardly as is conventional to facilitate drainage of rain and melting snow.

The reference numeral 40 denotes a clothes dryer embodying the present invention. Said clothes dryer is designed to be mounted on the window opening either at the outside of the double-hung window 26, as shown in FIGS. 1-5 and 7-11, or on the inside of the window as illustrated in FIG. 6. The dryer construction is the same for both so that a purchaser can place the dryer as desired.

The window casing sometimes includes side rails on the outside of the wall of a building within the window opening and similar side rails on the inside of a wall of a building in said opening. Other installations, such as the ones shown in FIGS. 1 and 7 do not include side rails, in which case the corresponding part 42, 44 of the window opening is exposed, i.e. the part which otherwise would be covered by the side rail, inasmuch as the window casing normally is recessed from the plane of the exterior surface of the building. It is in this inset space, either on the side rails, if they are present, or on the exposed portions of the sides of the window opening, if side rails are absent, that the clothes dryer 40 is mounted.

For the purpose of mounting, the dryer includes two brackets 46, one bracket at one side of the dryer and the other at the opposite side. As illustrated, each bracket is made of a single piece of metal and is formed at its opposite ends with angle-shaped terminations 48 each of which includes a first arm 50 that lies flat against a wall of a building, either the external or the internal wall, the external wall being the one illustrated in FIG. 1 and the internal wall being the one illustrated in FIG. 7, and a second arm 52 which lies against either the side rail, if one is present, or against a side surface of the window opening as shown in FIGS. 1-6 and 8-11. Each arm 50, 52 is formed with a through opening 54. Said opening is adapted to pass the threaded end 56 of a lag/machine screw 58. The lag end of the screw is anchored in the material of the building wall or in a lag sleeve inserted into a previously drilled hole in the building wall so that the screw is firmly embedded and there is no chance of it breaking loose so long

as the wall of the building is structurally sound. The machine end of the screw extends through the opening 54 to receive a wing nut 60. Thus, at each of the two terminations 48 of both brackets 46 two screws 58 and nuts 60 are provided to rigidly secure the associated bracket. It will be appreciated that with this arrangement it is quite easy for an unskilled member of the public to set in the lag screws and thereafter to rigidly attach the brackets, the only tool required being a drill, e.g. a star drill if the wall is brick, or a wrench if the wall is wood, in order to anchor the screws and, thereafter, a person's fingers sufficing to attach and tighten the wing nuts. The screws 58 can be emplaced on both the inside and outside of the window to permit the brackets and, therefore, the dryer to be rigidly attached to the sides of the window either inside or outside the window; it is a simple matter, since wing nuts are used, to shift the brackets and dryer from either location to the other. Then the bracket and dryer may be placed outside the window in the spring, summer and fall and inside the window in the winter.

Between the terminations 48 each bracket is shaped to provide a track 62 that is straight and of uniform configuration. The tracks are vertical and parallel to the sides of the window opening 22. The brackets are so mounted that the tracks are transversely registered with each other across the window opening. Although it is within the scope of the present invention to mount the brackets high in a window opening, the preferred mounting is such that the upper terminations are slightly below the lower frame member 64 of the upper sash 28 when the same is in its uppermost position (see FIG. 3). As later will be apparent this permits the dryer frame when in operative position to slide horizontally through the window opening at a height (below the raised upper sash) which is convenient for manipulation and convenient for loading articles on and unloading articles from the dryer frame.

A different shoe 66 is pivotally secured to each track 62 so as to permit swinging of the shoe with respect to the track about a fixed horizontal axis, the horizontal axes of pivotal movement of the two shoes being coincident. Although this can be accomplished with a rivet, in the preferred form of the invention the pivotal attachment is effected in such a fashion that the shoe can be connected to the track by a householder without the use of special tools. This permits assembly in the field and allows the dryer to be shipped in knocked-down condition. Indeed, as the description proceeds, it will be appreciated that the various parts have been so constructed that, to a large degree, the sundry component elements may be assembled into a completed dryer on the householder's premises by the householder himself, thereby enabling the dryer to be packaged for sale in compact form and also reducing the cost of the dryer by avoiding factory assembly. To the foregoing end, the pivotal means connecting each shoe to its associated track constitutes a flat-headed machine screw 68 (see FIG. 9) which has its head received in a countersunk opening 70 in the bracket at a height a few inches below the lower edge of the lower sash when the same is fully raised. The shank of the screw extends through a passageway 72 in the shoe and through an opening in the track to project beyond the track where it receives a wing nut 74. The shoe is so configured that it can act to captively slidably receive an elongated rectilinear element and, to this end, said shoe is fashioned

with an end-to-end trough 76 (see FIGS. 7, 8 and 9) having its base near the bracket and having an open mouth 78 remote from the bracket. The lips of the trough adjacent the mouth partially overhang the maximum width of the trough so as to prevent the slideable rectilinear element just mentioned from leaving the trough through the mouth 78. The wing nut 74 is tightened just enough to hold the screw 68 in position. It is not tightened enough to interfere with the swinging motion of the shoe relative to the track. Inasmuch as the rectilinear element, not yet described, desirably is slideable with ease in the shoe 66, the surface of the trough 76 which engages the rectilinear element, in this instance the entire surface of the trough, has a low coefficient of dynamic and static friction. This can be accomplished by making the shoe of metal and providing a slippery coating on the surface of the trough, e.g. a coating of Teflon or Kel-X (fluorocarbon resins). A simpler way of attaining the same purpose is to make the entire shoe of a slippery synthetic resin, e.g. a synthetic plastic such as polyethylene, the surface of which has a low coefficient of dynamic and static friction.

The shoes 66 are arranged to be swingable between a horizontal position (see FIGS. 3 and 4) in which the longitudinal axes of their troughs are perpendicular to the lengths of the tracks 62 and in which position the dryer is operative, as later will be appreciated, and a vertical position (see FIGS. 1 and 2) in which the longitudinal axes of their troughs are parallel to the lengths of the tracks 62 and in which position the dryer is stored against the building wall 20, as later will be described in fuller detail.

The structure providing axes of swinging movement has been pointed out hereinabove, the same constituting the screws 68. However, it is desirable to provide means for facilitating swinging movement of the shoes and for bracing the shoes in their horizontal operative position. Such bracing and movement facilitating means includes for each shoe and track a rider 80. The rider constitutes a body having a through opening 82 (see FIG. 10) through which the track 62 extends whereby the rider is slideable along the length of the track from the bottom termination 48 upwardly. Desirably, the riders move along the track easily and, for this purpose, the walls defining the openings 82 have a low coefficient of dynamic and static friction, said riders, as in the case of the shoes, being made of a polyethylene.

Each rider has a lug 84 with a vertical slot therein which receives the lower end of a link 86 the upper end of which is attached to the distal end of the shoe. The attachments of the ends of the link 86 to the lug 84 and the shoe 66 are pivotal, the pivots being horizontal, and the pivots of the two links being transversely registered. Although the pivots may be provided in any suitable manner such, for instance, as rivets, they are here shown as being screws and wing nuts similar to the screws 68 and wing nuts 74 mentioned in connection with the pivotal attachment of the shoes to the brackets. This likewise enables the parts just described to be shipped in disassembled (knocked-down) condition for compact packaging and assembly at the home rather than at the factory.

It will be apparent that when the riders are in a lower position (see FIGS. 3 and 4) the links 86 will act as struts to hold and brace the shoes in horizontal operative position and that when the riders are lifted (see

FIG. 2) they will raise the distal end of the shoes, swinging the same about the pivot screws 68 until the shoes are vertical. At their lower position (with the shoes horizontal) the lower surface of each rider 80 butts against an offset 88 (see FIG. 11) connecting the track 62 to the lower termination 48 whereby the weight of the shoes and anything carried by them will be transmitted through the struts 86 to the riders 80, then through the offsets 88 to the terminations 48, and, hence, to the sides of the window opening 22, so that the shoes are sturdily held in horizontal operative position. This transmission of forces particularly effective to support the shoes in such position because it is in this position that the shoes on both sides of the dryer carry the full weight of the drying frame and of the wet articles hung thereon.

However, full reliance for such transmission of the heavy weight involved is not placed solely upon such abutment and, moreover, there is the possibility that under certain wind conditions an upward force might be exerted upon the distal ends of the shoes which would undesirably cause them to raise despite the fact that the dryer is supposed to be in operative condition. Hence, the dryer, desirably, additionally includes means to releasably lock each rider in its lower dryer-operative position. Such means includes for each rider a locking pin 90 and a through opening 92 in the track 62 which opening is in registry with the pin 90 when the rider 80 is in dryer-operative position. The pin is reciprocally translatable horizontally so that it may be slid into and out of the opening 92, the rider being locked when the pin is in the opening. The tip of the pin is rounded to facilitate its entry into the opening 92. Although the pin can be translated by hand for locking and unlocking, in a preferred form of the invention the pin is spring-loaded toward locking position so that it will automatically lock when the rider reaches its lowermost position on the track and the householder will not be able to forget to effect locking movement of said pin. Accordingly, each pin is provided with a spindle 94 coincident with the longitudinal axis of the pin, the pin and the spindle being slideable in the central bore of a stud 96 extending from a face of the rider 80. A helical spring 98 is held under compression between the end of the pin 90 remote from the track 62 and the blind end of the bore in the stud, thereby urging the pin toward the track and into the opening 92 when the pin and opening are in registry. The rounded tip of the pin facilitates such automatic entry. When it is desired to retract the pin from the opening, a head 100 on the spindle 94, which extends through the blind end of the bore in the stud, is pulled out. The head of the stud includes a narrow flat-sided base 102 which is received in a mateable notch 104 formed at the tip of the stud 96. If it is desired to maintain the pin 90 in its idle position, the head of the spindle 94 is pulled out and turned 90° to locate the bottom of the base 102 in a position straddling the sides of the notch 104. Although not so shown in the drawings, the stud 96 may be screwed into a tapped aperture in the side of the rider 80, transferring assembly of the dryer from the factory to the home.

The shoes, links and riders are so dimensioned that when the riders are in their uppermost positions they will be short of the distal ends of the shoes (see FIG. 1), so as not to interfere with the same, and in their lowermost positions (see FIGS. 3 and 4) the shoes will be

held with their longitudinal axes perpendicular to the lengths of the tracks.

It will be recalled that the brackets 46 are so positioned that the upper termination 48 is below the lower frame member 64 of the upper sash when the same is in its uppermost position. Thereby when the shoes are swung to horizontal position (see FIGS. 3 and 4) said shoes are below the fully raised upper sash and also will be below the bottom of the lower sash when the same is fully raised. This arrangement is necessary to enable the frame, next to be described, to clear the two sashes as it moves between the interior (see FIG. 3) and exterior (see FIG. 4) of the building wall.

In order to assist the support of the shoes in their horizontal operative position, each link includes in its upper end a horizontal stop finger 106 that extends into the path of travel of the associated shoe as it swings downwardly. The stop finger is so located on the link that the shoe will be seated thereon when in its horizontal operative position (see FIGS. 3, 4, 7 and 8).

The dryer additionally includes a clothes supporting frame 108 which is of rectangular configuration and, like all of the other major structural components of the dryer, is shipped disassembled (knocked-down). Said frame is composed of eight major pieces. These include: two opposed transversely registered rectilinear elongated members 110, 112, i.e. side pieces, which conveniently are made of steel tubing, two end bars 114, 116 which preferably are straight and perpendicular to the members 110, 112 and when joined to them form a rectangle, and four corner connector pieces 118, 120, 122 and 124. The corner pieces are designed to join the members 110, 112 with the end bars 114, 116 and, for such purpose, each one is composed of two right-angled legs terminating at their tips in plugs 126 of reduced diameter. The diameters of the plugs are such that they are snug fits in the ends of the members and bars 110, 112, 114 and 116. Hence, with the connectors thrust into the ends of these members and bars the desired rectangular frame is formed. The connectors conveniently are made of a synthetic resin, an ABS (acrylonitrile-butadiene-styrene copolymer) being suitable and strong enough for this purpose. Inasmuch as the components of the frame are assembled in the home, it is not feasible to have the connectors force-fitted into the members and bars. Hence, the same are so relatively dimensioned that this fit is a slip fit and the connectors are positively secured to the members and bars as by screws (see FIG. 9). The end bars 114, 116 have plastic rods inserted therein to receive threaded ends of the hooks.

The members 110, 112 are slidable lengthwise in the shoes 66. Hence, the frame, as a whole, is slidable in these shoes, and with the shoes in horizontal operative position of the dryer the frame can be slid from a position in which it is mostly within a room (see FIG. 3) to a position in which it is extended from the room (see FIG. 4) so that it is exposed to the ambient conditions outside the building which usually, when the dryer is used, will be fresh air and the sun.

Inasmuch as the principal purpose of the dryer is to hang wet wash therefrom, said dryer includes suitable means for facilitating suspension of fabric items. Most conveniently, this means constitutes a clothes line or several lengths of clothes lines. As illustrated, several short lengths of clothes line 128 are provided. The end bars 104 incorporate standard means for attachment of

the clothes lines thereto, whether they be one or several. Said means may constitute hooks integrally formed from the material of the bar as, for example, tongues partially struck out from said bar material. Once again, to simplify assembly, said attachment means constitutes J-shaped hooks 130 each including a threaded shank 132. The shanks have self-tapping screws formed thereon so that they can be readily threaded by the householder into small pre-formed openings in appropriate positions in the end bars and into the plastic rods therein. At least certain openings are in registry with the plugs 126 (see FIGS. 9 and 11) so that they will be screwed into the plugs as well as through the bars, thereby securing the bars to the plugs. Desirably, the ends of the clothes line are formed with eyes 134 which are engaged to the hooks 130 with the line under a slight tension before the hooks are fully threaded into the end bars. Thereby, as the hooks are turned to fully engage the shanks with the end bars, the clothes lines will be tautened to ensure that the plugs 126 are firmly seated into the ends of the members 110 slidable in the trough 76.

The relationship between the shoes 66 and the frame 108 is one which permits, indeed, even encourages, ease of sliding movement of the frame relative to the shoes, this being particularly desirable when the frame and shoes are horizontally oriented so as to enable the frame to be slidable with minimum exertion between a location located substantially inside a room (see FIG. 3) for loading and unloading of articles on the clothes line in order to dry or air the same, and a location outside the window (see FIG. 4) at which the articles will be dried or aired in fresh air.

Nevertheless, this ease of horizontal movement of the frame with a possibly heavy load of articles thereon could be dangerous if the frame could move outwardly of the building without any check and fall on an innocent person in a street or yard. Hence, pursuant to a safety feature of the present invention, means is included to stop outward horizontal movement of the frame on the shoes beyond a point at which the frame disengages the shoes. Such means constitutes a positive stop and is in the form of an integral boss 136 (see FIGS. 1 and 3) on each of the corner pieces 118, 120, each boss projecting away from the associated corner piece in such a direction that its path of movement intersects the upper wall of the associated shoe 66. This wall of each shoe is shaped to provide a slot 138 the mouth of which faces toward the room when the frame is horizontal and downwardly when the frame is vertical. Thereby when the frame is pushed outwardly when in horizontal operative position the bosses will strike the bases of the slots to check further outward movement of the frame, thus preventing accidental outward discharge of the frame from the dryer to the street or yard below.

As an additional precaution, a back-up safety check means is included, the same having multiple functions, one being the back-up checking function, another being retention of the frame in a certain outthrust position when the shoes are vertical, which is to say, a position with respect to the shoes that corresponds to the said outthrust position of the frame when the shoes are horizontal and still another being retention of the frame in an unloading position when the shoes are horizontal. Said means constitutes spring-loaded pins 140 (see FIG. 8) similar to the pin 90, but cooperating with

openings 142 in the frame 108, actually a member 110, 112, instead of with openings in the track, as did the pin 90. The openings 142 are so positioned that they will be fully entered by the pins 140 when the frame is in the fully outthrust position of FIG. 4 with the shoes horizontal.

The pins 140 also are adapted to cooperate with two other pairs of openings in the frame 108. One pair of such openings is provided in the members 110, 112 in a position to be entered by the pins when the frame is retracted into the room to the position shown in FIG. 3. This later cooperation prevents the frame from being pulled roomwise to an extent sufficient to ride off the shoes. The other pair of such openings is provided in the members 110, 112 in a position to be entered by the pins when the frame is vertical and in the position shown in FIG. 11.

The same reference numeral 140 has been utilized to indicate the handle of the pin as well as the pin itself. The stud in which the pin is slidable, like the stud 96, can be detachably secured to the shoe by threaded interengagement and the same arrangement, i.e. notch and flat shank, can be used to enable the pin 140 to be disabled or to be spring-biased into any one of the three aforesaid openings in the frame. It will be appreciated from the foregoing description that shortly before the bosses 136 strike the bases of the slots 138 the rounded tips of the pins 140 will start to enter the opening 142 and that by the time the bosses are seated in the slots the pins will have fully entered the openings as illustrated in FIG. 8, thus applying an additional safety check.

Moreover, if the frame is now swung with the shoes about the pivot screws 68 to lift the frame to a vertical position, the frame will remain fixed with respect to the shoes, i.e. will not shift during the swinging step, thus preventing an accidental descent of the frame with possible harm to the user. However, after the frame and shoes have been swung to vertical position the pins 140 are pulled out of the openings 142 and the frame is permitted to descend under the user's control until sockets 144 (see FIG. 11) are telescopically received on protuberances 146 formed on the studs 96, thereby locking various parts of the dryer together by interengaging the frame 108 and riders 80. This interengagement is quite firm and will maintain the frame and shoes in elevated storage position and the riders in low position despite the imposition of stresses that may be imparted such, for instance, as a child pulling on the dryer if the dryer is stored inside a room, or wind blowing on the dryer if the dryer is stored on the outside of a building. It will be observed that with the frame in the locked position the entire weight of the dryer rests on the offsets 88 which, with the brackets, are rigidly attached to the wall of the building. In addition the pins 140 in the aforesaid vertical position of FIG. 11 will enter the aforesaid other of the two other pair of openings to assist in locking the frame in storage position.

To use the dryer, let it be assumed that it is in a storage position. This is a vertical position shown in FIGS. 1, 2 and 11 in which the sockets 144 have received the protuberances 146, the pins 140 are in the second of the other openings in the frame, the riders are in their uppermost positions shown in FIGS. 1 and 2, and the shoes 66 are in their vertical position as shown in the same figures.

The dryer illustrated in FIGS. 1 and 2 is on the outside of the building so that in stored position the frame is vertical and adjacent the wall of the building outside of the window. In this position close to the building the dryer does not present a projecting fire hazard; the dryer affords sufficient clearance beneath the bar 116 to allow free egress from the building.

To release the dryer, the pins 140 are pulled from the second of the other pair of openings in the frame, the frame is raised until the pins 140 are in their outermost locking position. Then the pins 90 are retracted from their associated openings 92 and the frame and shoes are swung outwardly until they are horizontal as shown in FIG. 4. At this time nothing is attached to the clothes lines 128 and the frame is entirely or largely outside the building. Next, the pins 140 are retracted from the outermost pair of openings in the frame and the user, pulling on the end bar 116, slides the frame in the shoes until the frame is largely inside the window and, therefore, in the room as shown in FIG. 3. In this position the pins 140 enter the first of the other pair of openings. Thereupon, the user places on the clothes lines whatever is desired to be hung therefrom such, for instance, as wet wash, articles to be aired, etc., and when this is finished and after the pins 140 are retracted from the first pair of the other openings, pushes the frame, still in its horizontal position, to a location outside the window as shown in FIG. 4, the motion-checking means preventing complete disengagement of the frame from the shoe. In its location outside the window the articles suspended from the clothes lines will have the benefit of fresh air drying and, if the sun is out, this drying not only will be speeded up but the articles will be subjected to the germicidal effects of the sun's rays. Moreover, if there is any wind blowing the drying will proceed even faster. The moisture evaporating from wet clothes will not accumulate inside the room. Finally, when the articles have been exposed to the ambient air for a sufficient length of time as, for example, when the wet wash becomes dry, the frame is pulled back into the room to the location shown in FIG. 3, the articles are removed and, if desired, fresh articles hung on the clothes line.

As has been indicated previously, it is not necessary for the dryer to be mounted on the outside of the wall of a building as shown in FIGS. 1-5 and 7-11. Alternatively, the dryer can be mounted on the inside of the room, this position being illustrated in FIG. 6. None of the parts of the dryer have to be changed for this change in location and the dryer will operate in the manner described above except that, when in its vertical storage location inside the room, the frame will hug the interior wall so closely that it takes up no noticeable amount of living space and can easily be concealed as by drapes.

Where the dryer is mounted in a casement window it is necessary for the brackets 46 to have the tracks located further away from the side walls of the window opening in order to clear the windows in their outswung positions. Moreover, because casement windows normally swing out, it is not usually practical to mount the dryer of the present invention on the exterior of a building in conjunction with casement windows. Hence, with casement windows an interior mounting such as illustrated in FIG. 6 is desirable.

It thus will be seen that there is provided a device which achieves the various objects of the invention and

which is well adapted to meet the conditions of practical use.

As various possible embodiments might be made of the above invention, and as various changes might be made in the embodiment above set forth, it is to be understood that all matter herein described or shown in the accompanying drawings is to be interpreted as illustrative and not in a limiting sense.

Having thus described the invention there is claimed as new and desired to be secured by Letters Patent:

1. A clothes dryer for use in conjunction with a wall of a building having a window opening with a window therein which window can be moved between open and closed positions, said clothes dryer comprising:

- A. an article supporting frame,
- B. means rigidly attached to the window opening to mount said frame on said wall at said window opening for shiftable movement between a horizontal operative position in which the frame is aligned with a space in the window opening provided when the window is open, and a vertical storage position against a surface of a wall of a building, said mounting means including
  - i. a pair of brackets securable permanently and rigidly to the sides of the window opening,
  - ii. the brackets including parallel tracks adjacent said sides,
  - iii. a pair of riders each slidable on a different track,
  - iv. a pair of shoes,
  - v. means mounting said shoes for pivotal movement about a common horizontal axis with respect to the window opening,
  - vi. each shoe having troughs the mouths of which face each other across the window opening and are in registry,
  - vii. a pair of links each associated with a different rider and affiliated shoe,
  - viii. each link being pivotally connected at one end to the distal end of the affiliated shoe and at the other end to the affiliated rider,
  - ix. said riders being movable between upper and lower positions whereby with the riders in upper position the shoes are vertical and with the riders in lower position the shoes are horizontal,
- C. said frame having parallel side members slidable in the troughs,
- D. means limiting outward movement of the frame with respect to the shoes when the shoes are in horizontal position and permitting unlimited inward sliding movement of the frame with respect to the shoes in horizontal position whereby the frame is dismountable from the frame mounting means inwardly of the building so as to permit the frame to be loaded inside the building either when the frame is mounted on the frame mounting means or when the frame is separate from the frame mounting means and yet to permit the frame, after being loaded, to be slid to a position external to the building, and
- E. pin and socket means on the riders and tracks to fix the riders in their lower positions on the tracks.

2. A clothes dryer as set forth in claim 1 wherein pin and socket means is included to releasably lock the frame mounting means in vertical storage position of the frame.

3. A clothes dryer as set forth in claim 1 wherein pin and socket means is included to releasably lock the frame in the frame mounting means when the frame is in horizontal operative position at a location outside the building.

4. A clothes dryer as set forth in claim 1 wherein pin and socket means is included to releasably lock the frame in the frame mounting means when the frame is in horizontal operative position at a location inside the building.

5. A clothes dryer as set forth in claim 1 wherein pin and socket means is included to releasably lock the frame in the frame mounting means when the frame is in vertical storage position.

15. 6. A clothes dryer as set forth in claim 1 wherein the frame is composed, in addition to the parallel side members, of end bars and connecting corner pieces, each corner piece disengageably engaging one end bar and one side member.

20. 7. A clothes dryer as set forth in claim 6 wherein means is provided to hold clothes lines taut between the end bars so as to firmly secure the side members to the corner pieces.

25. 8. A clothes dryer as set forth in claim 6 wherein the end bars carry hooks to which the clothes lines are attached and wherein at least one of the hooks includes a screw which extends through the associated end bar and is secured to the adjacent corner piece whereby to attach the corner piece to the end bar.

30. 9. A clothes dryer as set forth in claim 1 wherein the shoes are pivotally mounted on the tracks by screws and wing nuts.

35. 10. A clothes dryer as set forth in claim 1 wherein the shoes are pivotally mounted on the tracks by screws and wing nuts.

11. A clothes dryer as set forth in claim 1 wherein the ends of the links are pivotally connected to the ends of the shoes by screws and wing nuts.

40. 12. In combination, a building having a wall with a window opening therein, a window in said window opening, means mounting said window for movement between open and closed positions, and a clothes dryer comprising:

- A. an article supporting frame,
- B. means rigidly attached to the window opening to mount said frame on said wall at said window opening for shiftable movement between a horizontal operative position in which the frame is aligned with a space in the window opening provided when the window is open, and a vertical storage position against a surface of a wall of a building, said mounting means including
  - i. a pair of brackets securable permanently and rigidly to the sides of the window opening,
  - ii. the brackets including parallel tracks adjacent said sides,
  - iii. a pair of riders each slidable on a different track,
  - iv. a pair of shoes,
  - v. means mounting said shoes for pivotal movement about a common horizontal axis with respect to the window opening,
  - vi. each shoe having troughs the mouths of which face each other across the window opening and are in registry,
  - vii. a pair of links each associated with a different rider and affiliated shoe,

15

- viii. each link being pivotally connected at one end to the distal end of the affiliated shoe and at the other end to the affiliated rider,
- ix. said riders being movable between upper and lower positions whereby with the riders in upper position the shoes are vertical and with the riders in lower position the shoes are horizontal,
- C. said frame having parallel side members slidible in the troughs,
- D. means limiting outward movement of the frame with respect to the shoes when the shoes are in horizontal position and permitting unlimited inward sliding movement of the frame with respect to the
